(57) **CLAIM**

The ornamental design for a combined fire roasting and pot hook tool, as shown and described.

DESCRIPTION

FIG. 1 is a perspective view of a combined fire roasting and pot hook tool showing my new design including a handle section and a roasting section;

FIG. 2 is a left side view thereof;

FIG. 3 is a top view thereof;

FIG. 4 is a back view thereof;

FIG. 5 is a right side elevational view thereof;

FIG. 6 is a front view thereof; and

FIG. 7 is a bottom view thereof;

FIG. 8 is an assembly view showing how the sections are connected.

FIG. 9 is a left side view of the handle section, shown separately for clarity of illustration;

FIG. 10 is a top view thereof;

FIG. 11 is a back view thereof;

FIG. 12 is a right side elevational view thereof;

FIG. 13 is a front view thereof; and

FIG. 14 is a bottom view thereof.

FIG. 15 is a left side view of the roasting section shown separately for clarity of illustration;

FIG. 16 is a top view thereof;

FIG. 17 is a back view thereof;

FIG. 18 is a right side elevational view thereof;

FIG. 19 is a front view thereof; and

FIG. 20 is a bottom view thereof.

FIG. 21 is a left side view of the pot hook lifting section shown separately for clarity of illustration;

FIG. 22 is a top view thereof;

FIG. 23 is a back view thereof;

FIG. 24 is a right side elevational view thereof;

FIG. 25 is a front view thereof; and,

FIG. 26 is a bottom view thereof.

The broken lines showing the positioning of the connection points between sections are for the purpose of illustrating environmental structure and form no part of the claimed design.
